VENTILATING COWL

Filed April 22, 1935

UNITED STATES PATENT OFFICE

2,060,398

VENTILATING COWL

Edward D. Lenke, Akron, Ohio

Application April 22, 1935, Serial No. 17,556

6 Claims. (Cl. 126—299)

This invention relates to improvements in gas burning cooking stoves and particularly to an improved cowl for such stoves.

Objects of the invention are to provide a cooking stove having a cowl of simple, durable construction which may be conveniently operated and which will be very efficient in removing fumes and vapors formed by the operation of the stove.

Other objects are to provide a cowl which may be quickly and conveniently attached to a stove or to a wall above a stove and which is provided with an electrically operated exhaust fan arranged therein to draw the gases of combustion and cooking fumes from the stove and expel the same 15 from the room in which the stove is located.

Additional objects are to provide a cowl of the class above indicated which may be attached to or used in connection with practically any type of stove and which is provided with adjustable 20 means for operative attachment to stoves having any type of oven vent; to provide a cowl having a forwardly presented inlet opening arranged to receive the gases of combustion and vapor formed by the cooking operation and to provide 25 improved means for drawing the fumes and vapor from the vicinity of the stove and expelling the same through a chimney or other flue.

The above objects are accomplished and additional ends are attained by the novel construction, combination and arrangement of parts herein described with reference to the accompanying drawing wherein there is shown an illustrative embodiment of the invention, it being understood that the invention is not confined to 35 the exact form shown and that changes and modifications may be made or resort had to substitutions which come within the spirit of the invention as set forth in the claims hereunto appended.

40 In the drawing:—

Figure 1 is a front, elevational view of a stove equipped with a ventilating cowl constructed in accordance with this invention.

Figure 2 is a side elevational view of same,

45 Figure 3 is a vertical, sectional view taken as indicated by the lines 3—3 of Figure 2,

Figure 4 is a vertical, sectional view taken as indicated by the lines 4—4 of Figure 1.

Proceeding now to a detailed description of 50 the invention with reference to the particular adaptation thereof disclosed in the drawing, the numeral 5 is used generally to denote a stove which may be of any suitable construction and which is provided on the upper face thereof with 55 a plurality of gas burners 6. The stove 5 is pro-

vided with a suitable oven having the usual exhaust pipe 7. In the particular adaptation of the invention shown, the upper portion of the stove is provided with a back plate 8 on which is mounted the improved cowl 9.

The cowl 9 is provided with a horizontally disposed, rectangular base plate 10. The forward edge portion thereof is supported on the back plate 8 with the base plate 10 projecting rearwardly therefrom. The numeral 11 denotes a 10 rear wall, preferably of rectangular form, which projects upwardly from the rear edge of the plate 10 and the numerals 12 and 13 denote side walls which project forwardly therefrom. The side walls 12 and 13 may be of any suitable design. 15 As shown in the drawing, each side wall 12 or 13 is of the same width as the adjacent side of the base plate 10 and extend upwardly with the forward edge thereof curved inwardly, then outwardly to form a relatively wide upper portion which is of approximately twice the width 20 of the lower portion thereof.

The upper portion of each side wall 12 and 13 terminates in a forwardly projecting point 14 and presents an edge 15 which is inclined upwardly 25 and outwardly from said curved edge to the point 14 and an edge 16 which is inclined rearwardly and upwardly from said point 14. The upper edge of the side plates 12 and 13 are disposed in the same horizontal plane as the upper edge of 30 the rear wall 11.

The numeral 17 denotes a relatively narrow, forward wall which extends between the edges 16 of the side walls 12 and 13 with the upper edge thereof terminating in the horizontal plane 35 of the upper edges of the walls 11, 12 and 13. The numeral 18 denotes a bottom wall which extends between the side walls 12 and 13. The wall 18 is provided with a rear portion 18a which projects forwardly at an upward inclination from 40 the rear wall 11 along a line intermediate its height and a forward portion 18b which is arched upwardly in the form of a portion of a hollow cylinder with the forward edge thereof terminating at the lower ends of the edges 15. The forward portion 18b of the wall 18 provides a laterally disposed, downwardly presented cavity 19 which forms a cowl for the light 20 hereinafter described.

The numeral 21 denotes a casing preferably 50 composed of sheet metal. The lower end of the casing 21 is of rectangular shape and is adapted to receive the upper end of the walls 11, 12 and 13 which are suitably secured thereto. In the adaptation of the invention shown in Figure 4, 55

the forward wall of the casing 21 extends downwardly and forwardly to form the strip 17. The wall of the casing 21 converges upwardly from the rectangular lower end portion thereof to a 5 relatively smaller round upper end portion which terminates in a cylindrical pipe 22.

The rear wall 11 is provided with a rectangular opening in which is fitted a door 23 which is hingedly secured along its upper edge to the 10 wall 11. The door 23 is provided along each lateral side thereof with inwardly projecting sector shaped side walls which are suitably secured thereto with the apex of the sector shaped wall presented upwardly. The side walls are connected along the bottom edges thereof with an arcuate lower wall 25. The arcuate, lower wall 25 is provided with a circular opening 26 and the door 28 may be swung outwardly as shown by the dotted lines in Figure 4 to position the 20 arcuate wall 25 outside of the wall 11 for the purpose of mounting a vent pipe 30 in the opening 25.

The portion 18a of the wall 18 is provided with a circular opening 29 which is adapted to receive 25 the upper end of the pipe 30 which leads from the oven of the stove as hereinafter disclosed.

It will be seen that the side walls 11, 12 and 13 and the bottom wall 18 and the casing 21 completely enclose a cavity 21a except at the 30 forward side thereof which is provided with a downwardly presented rectangular opening 31. A bracket 32 is welded or otherwise secured to the upper side of the wall 18b with the end portions 33 and 34 projecting upwardly from each 35 end thereof. A ring 35 is suitably secured to the projecting end portions 33 and 34. A collar 36 is concentrically supported within the ring 38 by the radially arranged springs 37 and an electric motor 38 is suitably secured in the collar 36. 40 The motor shaft 39 projects upwardly from said motor and is provided on the upwardly projecting end thereof with a suitable fan 40, which is operable to force air upwardly into the flue 22.

The numeral 41 denotes a cylindrical sleeve 45 which is positioned around the fan 40 and which extends upwardly therefrom to the walls of the casing 21. Suitable conductor wires 42 are employed to operatively connect the motor 38 and the lamp 20 in an electric circuit. A switch 43 50 being provided for the motor and a switch 44 for the lamp 20.

The cowl 9 is mounted to position the cowl above the stove, with the elongated opening 31 disposed with its outer edge thereof in a longitudinal line extending from the lower end of the interior face of the flue 22 to a line extending forwardly of the burners 6 as indicated by the dotted line 45 on Figure 2. The sleeve 41 prevents air driven upwardly by the fan 40 from 55 returning to the cavity of the casing whereby all gases and vapors are efficiently driven upwardly through the flue 22.

While the improved ventilating device has been 60 illustrated and described in reference to a particular stove 5, it is understood that the same is adapted for use with any type of stove and that the cowl 9 may be manufactured as a separate unit and mounted in any suitable manner above a stove or other heating device.

Having thus illustrated my invention and described the same in detail, what I claim as new and desire to secure by Letters Patent is:—

1. In a device of the character described, a casing having a rectangular lower portion, an 65 upper portion converging upwardly from said 70

rectangular portion and terminating in a cylindrical flue, a bottom wall in said lower portion, said bottom wall inclined upwardly from the rear wall thereof and terminating in spaced relation to the forward wall thereof to provide a downwardly presented, elongated opening extending along the forward side of the casing, means to connect an open vent pipe to communicate with the interior of said casing, an electric motor mounted within said casing with the shaft thereof projecting upwardly, a fan mounted on the upwardly projecting end of said shaft and a cylindrical sheath having its upper end attached to the wall of said upper portion with the lower end thereof in communication with said casing and the upper end thereof in communication with said flue, said sheath projecting downwardly with the lower end thereof surrounding said fan. 15

2. In a device of the character described, a casing having a rectangular lower portion, an upper portion converging upwardly from said rectangular portion and terminating in a cylindrical flue, a bottom wall in said lower portion, said bottom wall inclined upwardly from the rear wall thereof with the forward portion thereof bulged upwardly to form a transversely arranged recess in the lower side thereof, said bottom wall terminating in spaced relation to the forward wall of the casing to provide a downwardly presented, elongated opening extending along the forward side of the casing, means to connect an oven vent pipe in communication with the interior of said casing, an electric motor within said casing, said motor mounted on the upwardly bulged portion of said lower wall with the shaft 30 thereof projecting upwardly, a fan mounted on the upwardly projecting end of said shaft and a cylindrical sheath positioned entirely within said casing with the upper end thereof communicating with said flue and the lower end thereof with the interior of said casing, said sheath having its upper end attached to the wall of said upper portion, said sheath projecting downwardly with the lower end thereof surrounding said fan. 35

3. In a ventilating hood for a cooking stove 40 having gas burners on the upper side thereof and an oven, a support adapted to project upwardly from the rear edge of said stove, a casing mounted on said support, said casing having a rectangular lower portion, an upper portion converging upwardly from said rectangular portion and terminating in a cylindrical flue, a bottom wall in said lower portion, said bottom wall inclined upwardly from the rear wall thereof and terminating in spaced relation to the forward wall of said 45 casing to provide a downwardly presented opening which extends along the forward side of the casing, a vent pipe adapted to lead from an oven and communicating with the interior of said casing at a point below said opening, an electric motor mounted within said casing with the shaft thereof projecting upwardly, a fan mounted on the upwardly projecting end of said shaft and a cylindrical sheath having its upper end attached to the wall of said upper portion so as to communicate with said flue, said sheath projecting downwardly with the lower end thereof terminating within said cavity surrounding said fan. 50

4. In a device of the character described, a casing, having a rectangular lower portion, a top portion having a side wall which converges from said lower portion to a cylindrical flue which projects upwardly from the upper end thereof, a bottom wall in said lower portion, said bottom wall inclined upwardly from the rear wall thereof 55

- with the forward edge thereof terminating in spaced relation to the forward wall of said lower portion leaving a space forming a downwardly presented inlet opening to the interior of said 5 casing, an oven vent pipe operatively attached to the lower portion of said casing and communicating with the interior thereof at a point below said inlet opening; an electrically driven fan mounted within said casing, said fan operable 10 to force air upwardly into said flue and a cylindrical sheath closely fitted to and attached to the wall of said upper portion with the upper end thereof presented to said flue, said sheath projecting downwardly with the lower end thereof 15 terminating within said casing and surrounding said fan.
5. In a ventilating device for a gas burning kitchen stove, a casing having a rectangular lower portion, an upper portion converging upwardly 20 from said rectangular portion and terminating in a flue; a bottom wall in said lower portion, the rear wall of said lower portion projecting downwardly beyond said bottom wall, said lower portion having a relatively short forward wall inclined outwardly from the lower edge of said upper portion, said bottom wall inclined upwardly 25 from the rear wall thereof and terminating in spaced relation to the forward wall thereof to provide a downwardly presented, elongated opening extending along the forward side of the casing; the forward portion of said bottom wall provided with a laterally extending, upwardly bulged
- portion forming a light cowl on the lower side thereof; a bracket secured to the upper face of said upwardly bulged portion; an electrically driven fan operatively mounted on said bracket; a cylindrical sheath having its upper end closely 5 fitted to and attached to the wall of said upper portion so as to be in communication with said flue, said sheath projecting downwardly with the lower end thereof terminating within said upper portion and surrounding said fan and means to 10 operatively connect an oven vent pipe to communicate with the lower, rear portion of the interior of said casing.
6. A ventilating apparatus for drawing fumes from a kitchen stove, comprising a casing having 15 walls which converge upwardly to a flue at the top thereof; means to support said casing over a stove, said casing having a downwardly presented air ingress opening along the forward side thereof, the lower wall of said casing extending rearwardly at a downward inclination from said ingress opening, said lower wall provided with a laterally extending, upwardly bulged portion conforming in shape to a portion of a hollow cylinder; means to operatively connect an oven vent 20 pipe to the lower portion of said casing at a point spaced rearwardly from said bulged portion and an electrically driven fan mounted on the upper side of said upwardly bulged portion for drawing air through said opening and vent pipe and dis- 25 charging the same through said flue.

EDWARD D. LENKE.
